UNITED STATES PATENT OFFICE.

FRANK J. HEIDEGER, OF BRIDGEWATER, PENNSYLVANIA, ASSIGNOR TO THE PHOENIX GLASS COMPANY, OF PITTSBURG, PENNSYLVANIA.

DESIGN FOR A SHADE.

SPECIFICATION forming part of Design No. 29,129, dated August 2, 1898.

Application filed April 23, 1898. Serial No. 678,672. Term of patent 14 years.

To all whom it may concern:

Be it known that I, FRANK J. HEIDEGER, a citizen of the United States, residing at West Bridgewater, in the county of Beaver and

5 State of Pennsylvania, have invented a certain new Design for Shades for Gas and Lamp Fixtures; and I do hereby declare the following to be a full, clear, and exact description of the invention, such as will enable others 10 skilled in the art to which it appertains to make and use the same.

This invention has relation to a design for shades for gas or lamp fixtures.

15 The accompanying drawing shows in side elevation a shade embodying my design.

The design consists of a shade having the scalloped bands E F, the round spots e, concentric with the scallops, and the stars f between the bands.

What I claim as my invention is—20 The design for a shade or similar article as shown and described.

In testimony whereof I have affixed my signature in presence of two witnesses.

FRANK J. HEIDEGER.
